UNITED STATES PATENT OFFICE.

CLARENCE L. BURGER, OF NEW YORK, N. Y.

MARINE VESSEL.

SPECIFICATION forming part of Letters Patent No. 681,417, dated August 22, 1899.

Application filed March 28, 1898. Serial No. 675,271. (No model.)

To all whom it may concern:

Be it known that I, CLARENCE LIVINGSTON BURGER, a citizen of the United States, residing at New York, (Pelham Manor,) in the 5 county of Westchester and State of New York, have invented a new and useful Improvement in Marine Vessels; and I do hereby declare that the following is a full, clear, and exact description of the same.

- 10 It is generally conceded by all familiar with naval warfare that a torpedo-boat that can approach within torpedo range of a warship and discharge a torpedo so as to strike the warship before being itself put out of action can 15 destroy any battle-ship or cruiser afloat and will revolutionize naval warfare. Surface torpedo-boats are designed to approach within range of a warship and hurl a torpedo, relying upon surprise and their high speed to 20 then escape destruction; but events have proven that the modern machine and rapid-fire gun and the search-light have made these frail and easily-vulnerable craft an enemy little to be feared either by day or night.
- 25 Submarine torpedo-boats have been designed to attack a warship while well submerged below the surface of the water, and thus protected from the fire of machine and rapid-fire guns; but such submarine boats 30 are open to the objection that while submerged the object of their attack is totally invisible, and it is thus impossible to guide the torpedo-boat in its direction, the fluctuations of the compass, the tides and currents, 35 and the movements of the boats themselves rendering useless any observations of the boat to be attacked taken from the torpedo-boat before its submergence while out of the long range of the enemy's guns. Further, sub- 40 marine boats are always liable to dive to the bottom when the diving apparatus fails to work properly or the trim of the boat is altered, for once inclined downward the forward impetus of the boat forces it downward 45 irresistibly. Other defects of the submarine boat are its inability to maintain its speed or its course for any distance below water owing to the exclusion of air, which prevents steam-power from being used and necessi- 50 tates the employment of storage batteries or other auxiliary motive power. Air for ventilation is of course also excluded and has to

be temporarily provided for by means of compressed-air apparatus.

The object of my invention is a torpedo-boat which has the advantage of the submarine boat in its absolute protection from injury by ample submergence beneath the waves, and yet, like the surface torpedo-boat, can be navigated from a conning-tower above 60 water and is always in communication with the atmosphere, so that air may always be had for ventilation and for combustion, thus permitting the use of the most efficient motive power.

I attain my ends by means of a submarine hull, containing the propelling means, working quarters, torpedo-gun or other means of offense, and the other vital parts, designed to travel at a fixed distance below the waves, so 65 as to be safe from hostile shot or attack, an upper hull or float, preferably of cellular construction and containing cellulose, so as to be non-sinkable, designed to ride over the waves and support the submarine hull, and 70 means for communicating between the submarine and surface hulls, and I prefer to employ an armored shaft forming a conning-tower above the surface hull, and through 75 which access may be had, and the necessary air-pipes, and signaling and steering connections, &c., led, to the submarine hull.

In order that my invention may be clearly understood, I shall first describe in detail the mode in which I carry the same into practice and then point out its various features in the claims.

Reference is to be had to the accompanying drawings, forming part of this specification, in which like letters of reference designate 80 the same parts in all the figures.

Figure 1 is a side elevation of a torpedo-boat embodying my invention. Fig. 2 is a sectional side elevation of the same. Fig. 3 is a plan view of the same. Fig. 4 is a sectional plan view on the line 4-4, Fig. 2. Figs. 5, 6, and 7 are cross-sectional views of the boat on the lines 5-5, 6-6, and 7-7, respectively, Fig. 2, the interior fittings being omitted.

I make the body or main hull A of the boat preferably of thin steel, of hollow and, generally speaking, cigar-like form, to travel usually about five to ten feet below the surface

of the water, and thus be absolutely safe from injury by hostile shot or projectiles.

The submerged hull A is provided with a suitable rudder H, a screw-propeller, (triple-5 screws are here shown,) and a suitable steam or other driving engine G, living-quarters for the crew, and at its forward end with, in this instance, two submerged torpedo-tubes H', through which torpedoes can be discharged 10 at a hostile vessel when the torpedo-boat is within range thereof, so as to sink and disable the same. All the torpedoes, fuel, stores, and other vital or essential appurtenances of the boat are also placed in the submerged 15 hull A, so that all are absolutely protected from injury by hostile shot or shell.

The submarine hull A is maintained the desired distance below the surface of the water by means of a long, preferably low, canoe-shaped float or hull C, designed to travel with little resistance along the surface of the water and ride more or less over the waves, with which float or hull C the submarine-hull A is connected by an air-shaft D, preferably armored, which rises from the top of the submarine hull through the surface float or hull C. The air-shaft D is elevated above the deck of the float or hull C to form an armored conning-tower D', having slits or windows 25 from which the boat can be properly navigated and steered like an ordinary boat, a working platform D² being provided for the navigator in the conning-tower. The steering apparatus for controlling the rudder H 30 on the submarine hull A and the signaling apparatus for communicating with the engineer, the torpedo-men, and the crew in general, are also by preference carried through the air-shaft D, within reach of the navigator 35 in the conning-tower.

The top of the conning-tower D' is made to open to give access from the deck of the surface hull C to the interior of the air-shaft and therethrough by means of steps or a ladder 45 to the interior of the submerged hull A. Openings E are provided at the top of the conning-tower for supplying fresh air to and exhausting foul air from the submarine hull A, suitable air-blowers and air flues or pipes being 50 provided for the purpose. Other openings F and suitable pipes are provided for discharging into the atmosphere the steam, products of combustion, &c., from the engine and the boiler in the submerged hull A.

55 Better to sustain the submerged hull A from the surface hull C, I prefer to connect the two by means of a rigid elongated hollow narrowed portion or web B, embracing the air-shaft D and of a form to pass easily through 60 the water, the web being constructed of thin steel and merging into the structures of the surface and submarine hulls.

I prefer to make the partially-exposed surface hull C, as well as the web B, of cellular 65 construction and to fill the cells with cellulose, cork, or other suitable material, so that even

when partially destroyed or perforated by shot or shell or other hostile appliances the hull C and web B will still have sufficient buoyancy to uphold the submerged hull A and 70 ride the waves. The displacement of the submerged portion of the boat being made only a little less than its gross weight, even a minor portion of the surface hull will suffice to sustain the submerged hull and its contents. 75

As the armored conning-tower is practically invulnerable to any but large-caliber shot, as large-caliber guns would stand very little chance, if any, of hitting so small a target as the conning-tower in motion, as the 80 non-sinkable surface hull would still be effective even if riddled with shot, and as, owing to the submerged hull being below the bottom of the surface hull and separated from the same by the water a shot striking or exploding on the surface hull would not injure the submerged hull, it seems almost certain that my torpedo-boat, with all its vital parts 85 deeply submerged and having ample driving power, could approach within torpedo range 90 of almost any warship afloat and destroy the same by a torpedo with but little danger of being itself disabled before it could escape.

It is evident that the surface hull C may be utilized as far as suitable like an ordinary 95 surface vessel. For instance, it may carry one or more machine-guns, above-water torpedo-tubes, &c., and, particularly in times of peace, a comfortable deck-house, &c., while its compartments or cells may be used, the 100 cellulose, if used, being temporarily removed for storage of fuel, supplies, &c.

I claim as my invention—

1. A boat comprising a surface hull, a submarine hull, and connecting and communicating means between said hulls. 105

2. A boat comprising a surface hull, a submarine hull, and a longitudinal web connecting said hulls.

3. A boat comprising surface and submarine hulls having independent bows, and connecting and communicating means between said hulls. 110

4. A boat comprising surface and submarine hulls having independent sterns and connecting and communicating means between said hulls. 115

5. A boat comprising a cellular surface hull, a submarine hull, and connecting and communicating means between said surface and 120 submarine hulls..

6. A boat comprising a canoe-like surface hull, a submarine hull, and connecting and communicating means between said hulls.

7. A boat comprising a surface hull, a cigar-shaped submarine hull, and connecting and communicating means between said hulls. 125

8. A boat comprising a surface hull, having a canoe-like bow, a submarine hull, and connecting and communicating means between 130 said hulls.

9. A marine vessel comprising a boat-like

- surface hull, a submarine hull and connecting and communicating means between said hulls.
10. A boat having a canoe-like surface hull and a habitable submarine hull depending from the bottom of the canoe-like surface hull, and having an air-shaft rising thereto.
11. A boat having a hull to travel on the surface, a submarine hull suspended from the surface hull, and an armored air-shaft connecting the submarine hull with the surface hull and forming a conning tower above the surface hull.
12. A boat having a surface hull, a submarine hull supported from the surface hull by a longitudinal web, and an air-shaft connecting the submarine hull with the surface hull.
13. A boat having a non-sinkable surface hull, a cigar-shaped submarine hull supported from the surface hull and containing the operating parts of the boat, and an air-shaft connecting the submarine hull with the surface hull.
14. A boat having a surface hull, a submarine hull, an elongated non-impeding hollow web, and an air-shaft extending therethrough connecting the two hulls.
15. A boat having a canoe-like surface hull and a cigar-shaped submarine hull supported from the surface hull and having an air-shaft 30 rising thereto.
16. A boat having a surface hull and a habitable submarine hull depending from the bottom of said surface hull and having an air-shaft rising thereto.
17. A boat comprising a surface hull, a habitable submarine hull and means, including an air-shaft, for connecting the surface and submarine hulls.
- In testimony whereof I have hereunto set my hand the 15th day of March, 1898.
